EXTENSIBLE CHUTE

Willard E. Blain, Van Buren, Ark.

Application March 7, 1940, Serial No. 322,858

15 Claims. (Cl. 227—37)

This invention relates to improvements in life saving apparatus, although this designation does not denote a true scope of use thereof. When considering the invention as an extensible chute the variety of its possible uses embraces life-saving, fire-fighting, conveying, elevating and analogous uses. Therefore on the latter principle this description is confined to the use of the apparatus as a life-saving device in order that one of its modes of employment will be fully understood.

In attempting to save the life of an endangered person it is necessary to reach him with a contrivance of some sort in order that he will be conducted to a place of safety. This is true whether the person is trapped in a burning building or is thrown into the sea. In either case it is highly desirable to have a contrivance with which to reach out over the intervening space and provide said person with a means of escape. The instant invention is founded upon the use of a flexible-rigid strip which is flexible from the standpoint of its capability of being wound up, and rigid from the standpoint of its remaining perfectly stiff when extended out from its point of anchorage. With this premise in mind the objects of the invention are as follows:

First, to provide an apparatus which in the interest of brevity is entitled an extensible chute but which is not confined to any such limitation in its use as its designation might imply, said chute being primarily intended for use as a life-saving device in which respect it is an adjunct to fire-fighting apparatus.

Second, to provide an apparatus of the foregoing generic aspect, fundamentally comprising an extensible member of the flexible-rigid type, said member consisting of a strip, usually of metal, which is self-sustaining when extended, because of its cross-sectionally concavo-convex form.

Third, to provide a chute of the foregoing character which is capable of being used either as a rope ladder support or as a water tower, or both at the same time, all as clearly brought out below.

Fourth, to provide an extensible chute which is capable of quick and easy adjustment both vertically and laterally so that its free terminal is capable of being directed to the position of the endangered person in a matter of very short time.

Other objects and advantages will appear in the following specification, reference being had to the accompanying drawings, in which:

Figure 1 is a vertical section of the base of the

extensible chute, particularly illustrating the actuating mechanism.

Figure 2 is a horizontal section taken on the line 2—2 of Fig. 1.

Figure 3 is a vertical section taken on the line 3—3 of Fig. 1 illustrating the chute guide.

Figure 4 is a plan view of most of the structure illustrated in Fig. 1.

Figure 5 is a vertical section taken on the line 5—5 of Fig. 4, particularly illustrating the brakes.

Figure 6 is a partially sectional and elevational view illustrating a life-saving feature more in detail.

Figure 7 is a plan view of the extensible chute, illustrating its use as a water tower.

Figure 8 is a detail plan view of the free terminal on a scale slightly enlarged from the showing in Fig. 7.

Figure 9 is a view on the order of Fig. 8, but showing how a rope ladder may be laid along the trough of the chute.

Figure 10 is a cross section taken on the line 10—10 of Fig. 8.

Figure 11 is a cross section taken on the line 11—11 of Fig. 8.

Figure 12 is a longitudinal section taken on the line 12—12 of Fig. 8.

Figure 13 is a view somewhat similar to Fig. 12 but illustrating the suspension of a rope ladder from the free terminal of the chute.

Figure 14 is a sectional view of a portion of the chute illustrating a laminated support.

Figure 15 is a cross section taken on the line 15—15 of Fig. 14.

In carrying out the invention use is made of a chute 1 which is herein known as of the flexible-rigid type. This apparently paradoxical term is correctly expressive of the nature of the chute because while the latter is perfectly rigid when extended yet it is inherently so flexible that it is capable of being wound upon a drum. The reason for its nature lies in the fact that it is made of thin flexible metal, preferably steel, of concavo-convex form in cross-section.

This latter form (Fig. 4) has its additional usefulness in the provision of a trough down which a person can slide, or down which inert objects can be slid as on a conveyor. This chute 50 has its lower portion 2 (Fig. 1) wound upon a drum 3. Prior to the beginning of the winding said chute takes a gradual bend at 4, and as it bends its cross-sectional curvature disappears so that the convolutions of the wound portion 2 lie perfectly flat upon the drum. This bending is

facilitated to some degree by a fixed guide 5 (Fig. 3).

Said guide is rigidly supported by standards 6 which are bolted down or otherwise secured to a horizontally pivoted table 7. The horizontal pivoting is derived from the mounting of boxes 8 on the nether side of the table 7 upon a horizontal shaft 9 which is set at its ends in supports 10.

It is immaterial whether the boxes 8 turn upon the shaft 9 or the shaft is made to turn in the supports 10. In the former instance the shaft would be clamped to the supports while in the second instance the boxes 8 would be clamped to the shaft. In either case the pivoting of the table is horizontal, but its permissible motion is in a vertical plane. This allows for the raising and lowering of the chute 1 when the latter is extended, as in Figs. 1 and 9.

The bottom terminal 11 of the chute 1 is anchored in any desired way. A preferred mode of anchorage is to slot the shaft 12 of the drum 3 as at 13, for the admission of said terminal 11 after the latter has been slipped into a passageway 14 leading from the face of the drum to a place of registration with the slot 13. In any case it would be desired and necessary to firmly anchor the terminal 11 so as to avoid any chance of its ever becoming loose.

The drum 3 and wound chute portion 2 are housed in a casing which is rigidly attached to standards 16 bolted to the table 7, and being erected therefrom as shown in Fig. 1. The holding of the casing 15 is accomplished by a long cross bolt 17 (Fig. 2) which goes through ears 18 that are pendant from the casing, and then through bosses 19 on the standards before the nuts 20 are screwed home. Other but short bolts 21 are screwed through bosses 22 on the standards into the adjacent heads 23 of the casing 15 (Fig. 6).

Thus the casing 15 is held very firmly during the winding and unwinding of the chute 1. The latter has access to the interior of the casing through a sufficiently large opening 24 (Fig. 1). The nature of the trough 1 is such that there must be insurance against the possibility of the wound portion 2 slipping to any undesirable degree. It is true that other provisions are made against this contingency, but from the standpoint of keeping the convolutions tight, use is made of an enveloping band 25 (Fig. 1) which is anchored at 26 at one end and curved at the other free end 27. This band is pressed upon by a number of stout leaf springs 28. These springs are contained by the casing 15 to which one end of each is riveted at 29. The other end of each spring rides free against the interior of the casing, but the original tension of each spring is such that it tends to bow inwardly to quite a large extent, thus always insuring adequate pressure against the enveloping band. The latter remains constantly adjusted to the size of the wound portion 2 whether large or small.

Winding and unwinding of the chute is accomplished by a crank 30 on one end of the shaft 12 (Fig. 4). The use of a brake 31 (Fig. 5) in conjunction with this shaft is desirable. After the shaft has been turned the desired amount, the brake is set, thereby to hold the shaft from 70 undesired turning. The latter carries a brake drum 32. This has an external contraction band 33 applied to it, said band having a chute 34 in actual contact with the periphery of the drum. One end of the band is anchored at 35 (Fig. 5) 75

to a casting 36. This casting is secured at 37 to an appropriate portion of the table 7. It includes at least one ear 38, to which the brake lever 39 is pivoted at 40. Said lever has a short arm 41 to which the free end of the band 33 is attached. The swinging of the lever either loosens or tightens the brake band and the adjustments of the lever are set by means of a detent 42 which engages the teeth of a quadrant 43 made integral with the casting 36.

It is obvious that the turning of the shaft 12 will extend the chute 1, or retract it, depending upon the direction of turning, but these functions are preferably transferred to a moving and gripping mechanism 44 (Fig. 1), largely confining the function of the shaft 12 to the elimination of slack in the convolutions 2. But it is necessary to operate the shaft 12 in conjunction with the mechanism 44 because in actual practice the chute 1 is quite large and must be manipulated from the two points so as to insure a proper performance.

The mechanism 44 consists of two shafts 45, and 46, one below and the other above the chute 1. Each of these shafts has a core 47 which is faced with a rubber covering 48. The result of this construction is a roller below and above the chute, said rollers now being designated 49, 50, for distinction.

It is conceivable that each of the rollers may consist of a solid rubber body attached directly to the respective shaft. However, because of the size of the rollers, it is preferred to use a core because if and when this is made of wood, the constructional cost is lessened to a considerable degree. These rollers are contoured to fit the cross-section of the chute 1. Consequently the roller 49 is concave (Fig. 2) while the roller 50 is convex (Fig. 4). Obviously the roller 49 40 constitutes the major support of the chute 1 inasmuch as it is situated underneath and carries much of the weight of the chute while the roller 50 is largely in the nature of a hold-down since it works in the trough of the chute.

These rollers are in tight frictional contact with the chute. The shafts 45, 46, are inter-gearred at 51 (Fig. 4). One of the shafts carries a crank 52 (Fig. 4) for turning. The turning of the one shaft causes the turning of the other shaft by means of the gearing, the directions of turning always being opposite. The result is either an extension or retraction of the chute and since the mechanism 44 is situated out beyond the bend 4 and its contiguous guide 5, it is regarded as being in the best possible position for an effective manipulation of the chute in the manner named.

Now it is readily seen that main reliance for the extension and retraction of the chute is best put upon the mechanism 44. If the turning of the drum 3 were depended upon, especially for the extension of the chute, it is conceivable that some buckling of the convolutions 2 might occur in the casing 15 despite the holding function of the band 25. At the same time the drum and shaft 3, 12, are necessary to assist in feeding out and coiling the chute so said drum, shaft and mechanism 44 are desirably worked in combination for the best handling of the chute, as previously suggested.

Brackets 53 provide bearings for the shafts 45, 46. These brackets are bolted down on the table 7. In order to accomplish the gripping function of the mechanism 44, one of the shafts, preferably 45, is furnished with a brake 54 (Fig.

5) virtually identical with the brake 31. Being such it includes a casting 58 suitably secured to the table 1, providing a bearing for the brake lever 56 which actuates the brake band 57. The brake 54 is especially important from the standpoint of its being able to hold the chute 1 in any position of extension. The chute will not be able to slip past the rubber faces of the rollers in either direction.

The chute 1 is desirably guyed when extended 10 (Fig. 7), especially to a considerable degree. For this purpose wires 58 are used. There is a pair of these wires, each being wound at one end upon an independent drum 59 (Fig. 4) on the virtual extremities of a common cross shaft 60. 15 This shaft is journaled in bearings 61 which constitute the top terminals of brackets 62 bolted to and erected from the heads 23 of the casing 15 (Fig. 6). At least one of the ends of the shaft 60 is squared (preferably both as in Fig. 20 4) for the application of a crank 63, so that the shaft can be turned. A pawl and ratchet (commonly designated 64), serve to hold the drums 59 and wires 58 at tight adjustments. The latter are accomplished when the hooks 65 at the other 25 ends of the wires (Fig. 7) are fitted into eyes 66 at the free terminal 67 of the chute 1.

Said free terminal has a long slot 68. Actually this slot constitutes an opening large enough for the passage of a person. The result of the slot 30 68 is a pair of arms 69. These arms are kept rigid by the extension of the side curvatures of the chute virtually the full length of the arms. In other words, the side portions of the chute that extend along the arms function as reinforcing ribs.

Said arms are curled at 70 (Fig. 12) to compose hooks. These hooks are desirable for attaching the top of the chute to a window sill 71 or some equivalent of it. A person trapped 40 in a burning building of which this sill is a part, can easily step across the sill and through the opening 68 onto the rungs 72 of a rope ladder 73. This ladder is suspended from eyes 74 at almost the very extremity of the chute, use 45 being desirably made of large hooks 75 with which to make the attachment.

A step 76 is used in conjunction with the chute 1 at the free terminal 67. The latter is intended to embrace a considerable area, but would not 50 be considered as extending below the step 76. Said step is firmly affixed to the chute by welding, and it is braced by brackets 77 which insure the support of any normal weight. The step 55 is desirably flanged at 78. In practice the distances of the bottom of the slot 68 and the step 76 from the hook extremity will be so proportioned that a person can pass through the window at the sill 71 onto the step 77 preparatory to passing through the opening 68 to the rope 60 ladder.

Usually the rope ladder 73 will be employed in its pendant position as indicated in Fig. 13. But out of consideration of the possibility that this use of the ladder may require its passing 65 through a danger zone, for example a place where fire is emerging from a lower window, it is proposed to use the trough of the chute 1 as a receptacle, so to speak, for the rope ladder. In this case the rope ladder is led as seen in Fig. 9. The concave shape of the chute will insure retaining the latter so that a person can walk down the ladder in the chute without having to pass through any danger zone.

Figures 7 and 12 illustrate one main departure 75

from the primary use of the chute as a life-saving device. This departure converts the chute into a modified water tower. A hose 79 is laid in the trough of the chute. A hole 80 in the step 76 provides for the passage through the hose. The nozzle 81 of the latter is supported contiguously to the opening 68 by a clamp 82 which holds the hose down. The clamp can be of any desired form whatsoever, a suggested arrangement consisting of the hinged element shown in Fig. 10, the free end of which is adapted to be secured by a swinging bolt and nut 82.

All of the assemblage embraced by the foregoing description reading up from the table 1, is capable of adjustment as a unit when said table is tilted on the axis of the shaft 9. The tilting is done through a gear quadrant 84 (Fig. 1) which is driven by a pinion 85 in mesh therewith. The quadrant can be as great in angular extent as desired, naturally the greater the extent of the quadrant the greater will be the amount of angular adjustment of the table 1. The quadrant may be attached to the table in any preferred way, for example, by the flanges 86 and bolts 87 (Figs. 1 and 2). A shaft 88 carries the pinion 85. The shaft is turnable by a crank 89 and the adjustments are held by a dog 90 which is pivoted at 91 to a bracket 92 extending out from the bearing 93 of the shaft.

Said bearing and the supports 10 are carried by a turntable 94. This turntable is disposed horizontally, and it mainly comprises a large worm gear inasmuch as it has teeth 95 of that description on most of its circular perimeter (Fig. 2). Said turntable has a pair of extensions 96 to which the supports 10 are bolted at 97. The extensions are formed by forking the turntable at 98. The result of the fork is a passageway for the gear quadrant 84. The latter is operable in the passageway regardless of the angular position of the turntable 94 and the latter can be turned with the chute 1 in any of its extended positions, while the chute is in the process of extension.

The turntable 94 is large enough for several men to stand upon for the manipulation of the various cranks. But at this point it is desired to modify the implication of manual operation which the various cranks convey because there will be instances when the shafts to which the cranks are now attached will be worked to better advantage by driven machinery. The use of such driven machinery is regarded as an obvious expedient, and for that reason hand cranks are shown merely to simplify the illustration.

A worm gear 99 meshes with the teeth 95 (Fig. 2), the shaft 100 of said gear also carrying a crank 101 for its operation. This shaft could well be operated by a mechanical drive because of the considerable weight which it is required to move. The bracket supports 102 of the shaft 100 are fastened to the bed 103 of a truck or equivalent conveyance. Said bed might well be a part of the chassis of an apparatus such as is commonly seen for the mounting of ladders in fire-fighting apparatus.

An opening 104 (Fig. 1) which in actual practice is not essential, makes room for the securing means 105 with which the stud 106 of the turntable 94 is held to a fixed ball race 107. Said race is affixed to the bed 103 by bolts 108. It supports a series of balls 109 on which the nether race 110 of the turntable 94 runs.

The arrangement in Fig. 6 is employed in such

instances wherein the chute 1 is used as a safety slide for an endangered person. The disposition of the latter in Figs. 9 and 13 provide alternate modes of escape when a person is able to walk down a ladder. The arrangement in Fig. 6 provides for his sliding to safety in the event of his either being injured or too timid to negotiate the ladder. A curved shield 111 (Fig. 6) is used in conjunction with the chute 1, said shield being cross sectionally contoured to fit the concavity of the chute. Said shield is firmly supported by a bracket 112 from the casing 15 to heads 23 of which the bracket is riveted at 113.

The shield 111 is higher than any of the actuating mechanism in Fig. 1, and necessarily so in order that the person may slide directly into a life-saving net 114 (Fig. 6). This net is intended to be of any conventional order and its manner of support is of no immediate concern. It is sufficient to note that the net is located close to the offtake side 115 of the shield so that a person sliding over the latter is directly caught by the net.

Attention is now directed to Figs. 14 and 15 which disclose a possible reinforcement of the chute now designated 1a. The latter is intended to be made in such a way that it will possess ample strength when composed of single ply metal. By way of digression it should be noted that the chute tapers in width (Fig. 7) from its base at the drum 3 to its free terminal 67. But the chute is also intended to be tapered in thickness between two extremes. This taper is denoted mainly in Fig. 14, which view is also used for a showing of a laminated support 116.

This support is much on the order of the leaves of a spring. They are successively shorter toward the base of the chute 1a, but all are interfitted because of being cross-sectionally curved in agreement with the contour of the chute. These laminations will be wound on the drum 3 with the chute, and when they are thus wound then the enveloping band 25 has the added importance of keeping the free edges of the laminations from extending out from the convolutions of the wound portion 2.

The operation is readily understood. The apparatus is mounted on the bed 103 of a truck in the instance of its being an adjunct to a city fire-fighting apparatus. It is readily conceivable that the nature of the chute 1 insures its extending out in a perfectly rigid manner. When thus extended it is used either as a ladder support (Figs. 9 and 13) or a hose support (Fig. 7). Another use is that of a slide as seen in Fig. 6.

It is intended that the chute will also be well adapted to use aboard ship. A person swept into the water can be rescued by extending the chute until its free terminal 67 is moved out within reach. It is thought unnecessary to enlarge upon other uses of the chute because these will and must suggest themselves to the actual practical application of its principles.

I claim:

1. Apparatus of the character described comprising a cross-sectionally concavo-convex chute of thin flexible material, means in reference to which one end of the chute is windable and unwindable, actuating mechanism to retract and extend the chute, said mechanism including rollers which respectively are convex and concave to conform to the cross-sectional shape of the chute and being in close contact therewith to grip it firmly and hold it in any of its positions of extension, and guide means located be-

tween the winding means and said actuating mechanism to establish a predetermined pitch of the chute and to aid in flattening the concavo-convexity of the chute immediately in advance of its windings.

2. Apparatus of the character described comprising a cross-sectionally concavo-convex chute of thin flexible material, means in reference to which one end of the chute is windable and unwindable, actuating mechanism to operate the chute for its retraction and extension, said mechanism including a pair of rollers peripherally shaped to fit the respective concave and convex cross-sectional contours of the chute and gripping the surfaces of said chute tightly to hold the chute in any of its positions of extension, and guide means located between the winding means and said actuating mechanism being set at a pitch to aid in bending the chute prior to its winding, also to flatten the concavo-convex cross-section in the bending zone.

3. Apparatus of the character described comprising a flexible-rigid chute, means in reference to which one end of the chute is windable and unwindable because of its flexibility, means exerting pressure upon the wound portion of the chute to tend to eliminate slack, and actuating mechanism including rollers tightly engaging opposite sides of the chute for its retraction and extension in respect to the winding and pressure means, said rollers serving to hold the chute in any of its positions of extension.

4. Apparatus of the character described comprising a flexible-rigid chute, means in reference to which one end of the chute is windable and unwindable because of its flexibility, an enveloping band surrounding the wound portion of the chute, being anchored at one end and free at the other end to allow for the enlargement and reduction in size of said wound portion, plural pressure means bearing on the band, keeping it in contact with said wound portion to eliminate slack, and combined actuating and gripping means for the chute including rollers which are operable to retract and extend the chute and are in tight engagement with opposite surfaces of the chute to hold it in any of its positions of extension.

5. Apparatus of the character described comprising a flexible-rigid chute, a drum on which one end of the chute is windable and unwindable because of its flexibility thereby to take up and let out the chute convolutions, actuating mechanism including rollers in tight contact with opposite sides of the chute, being operable to retract and extend the chute in reference to the drum, means with which to turn the drum, means with which to turn the rollers of the actuating mechanism, and separate brake devices for the drum and actuating mechanism respectively to hold the drum and rollers stationary.

6. Apparatus of the character described comprising a substantially horizontal tiltable table, a revoluble drum and a pair of revoluble rollers both mounted upon the table to assure a firm foundation therefor, a flexible-rigid chute tightly gripped between the rollers and having a contiguous end wound upon the drum, the other and free end of the chute extending out from the rollers and being self-sustained because of the rigid character of the chute, guide means also carried by the table, being located between the drum and rollers, and set at a pitch in reference to the table to establish a predetermined pitch

of extension of the free end of the chute, and means to tilt the table thereby to direct the position of the free end of the chute.

7. Apparatus of the character described comprising a tilttable table, a revoluble drum and a pair of revoluble rollers mounted upon the table, a flexible-rigid chute tightly gripped between the rollers and having a contiguous end wound upon the drum, the other and free end of the chute extending out from the rollers and being self-sustained because of the rigid character of the chute, guide means located between the drum and rollers, being set at a pitch in reference to the table to establish a predetermined pitch of extension of the free end of the chute, a turntable on which the tilttable table is mounted, and means carried by the turntable being operable upon the tilttable table to shift the position of the free end of the chute.

8. Apparatus of the character described comprising a horizontally turnable turntable, a horizontal shaft carried thereby, a table mounted on said shaft and therefore vertically tilttable, separate means for actuating the turntable and the tilttable table, providing for the adjustments of said tables in the horizontal and vertical planes, a drum and a pair of rollers mounted upon the tilttable table and therefore subject to the respective adjustments of the tables, a flexible-rigid chute tightly gripped by the pair of rollers and having its contiguous end wound on the drum, means for operating the drum and the rollers to extend and retract the other and free end of the chute, and a guide fixed upon the tilttable table between the drum and pair of rollers, being set at a pitch to determine an initial pitch of the chute in reference to the tilttable table.

9. Apparatus of the character described comprising a vertically tilttable table, a drum and a pair of rollers revolvably mounted upon said table, a flexible-rigid chute gripped on opposite sides by the pair of rollers, and having its contiguous end attached to and wound on the drum, the other and free end of the chute extending out into space, guide means to establish and maintain the pitch of the chute in reference to the table, and means to brace the chute at any of its degrees of extension comprising at least one guy wire attached at one end to the chute, and a drum on which the other end of said wire is wound.

10. Apparatus of the character described comprising a vertically tilttable table, a revoluble drum and a pair of rollers mounted on said table, a casing affixed to the table, containing the drum and having an opening, a flexible-rigid chute tightly gripped by the pair of rollers and having its contiguous end attached to and wound upon the drum, said chute being movable in the casing opening, guide means located between the casing and pair of rollers fixing the pitch of the other and free end of the chute in reference to the table and in its position in reference to the

pair of rollers, and guy means to assist in sustaining said free end of the chute, consisting of at least one guy wire having one of its ends attached to the chute, and a drum to which the other end of said wire is attached and wound, said drum being mounted upon the casing thereby to follow all adjustments of the chute.

11. Apparatus of the character described comprising a drum and a pair of rollers, a flexible-rigid chute gripped by the rollers and having its contiguous end wound on the drum, means for revolving the drum and the rollers to extend or retract the other and free end of the chute, a table on which both the drum and rollers are mounted to provide a firm foundation therefor, means supplying a horizontal axis to support the table for tilting in the vertical plane, and means for accomplishing the tilting of the table comprising a gear quadrant fixed to the table and an operable pinion in mesh with the teeth of said gear.

12. Apparatus of the character described comprising a single and unencumbered flexible-rigid chute of concavo-convex cross-section, a drum to which one end of the chute is attached and on which said end is wound, actuating means for moving and gripping the chute thereby to extend the other and free end thereof straight out from said actuating means, and then to rigidly hold said chute in the adjusted position, and means embodied in said free end of the chute whereby attachment can be made to an external support to guard against inadvertent sagging under a load.

13. In apparatus of the character described, a chute consisting of thin flexible material, being of concavo-convex cross section to impart rigidity thereto when extended, one end of said chute being slotted to afford a passage to and define a pair of arms, and hook formations on the extremities of said arms for engagement with an external support to thus laterally stabilize the chute at said slotted end.

14. In apparatus of the character described comprising a chute of thin flexible material being of concavo-convex cross section to impart rigidity thereto, means from which said chute is extensible so that its free end is held unsupported in space, and means strengthening the chute when made in unusual lengths, consisting of laminations underlying the chute and matching the concavo-convex cross section thereof.

15. Apparatus of the character described comprising a drum and a pair of rollers, said drum and rollers being revoluble, a flexible-rigid chute tightly gripped by the rollers for extension and retraction and having the contiguous end attached to and wound upon the drum, said chute being of concavo-convex cross section to define a trough down which a person may be slid and a shield overlying the drum and rollers, merging with the concavity of the chute to intercept said person.

WILLARD E. BLAIN.
